FOLDING CHAIR

Aristetie J. Antipas, Los Angeles, Calif.

Application May 7, 1934, Serial No. 724,270

6 Claims. (Cl. 155—147)

The present invention is an improvement in folding chairs of the kind disclosed in my Patent No. 1,604,108, dated October 26, 1926.

It is an object of the invention to provide such chairs with side arms so connected to the chair back as to be automatically brought to side arm position concurrently with the unfolding of the chair from a collapsed to an open usable position. Also it is an object to provide means acting through the arms to limit the opening movement of and to brace the back in open position.

Importantly, it is an object to provide a chair of this class in which all of its parts are self-effective; that is, it is not necessary to manually connect or disconnect any of the several elements when either folding or unfolding the chair; all parts automatically taking their intended positions, in either adjustment, when the chair is opened or closed. In other words there are no parts which must be hooked or unhooked or fastened or loosened in any way when the chair is to be set up or collapsed.

The invention consists in certain advancements in this art as set forth in the ensuing disclosure and having, with the above, additional objects and advantages as hereinafter developed, and whose construction, combination and details of means, and the manner of operation will be made manifest in the description of the herewith illustrative embodiment; it being understood that modifications, variations and adaptations may be resorted to within the scope, principle and spirit of the invention as it is more directly claimed hereinafter.

35 Figure 1 is a perspective of the unfolded chair.
Figure 2 is a front elevation of the unfolded chair,

Figure 3 is a vertical cross-section thereof; the back not being fully opened.

40 Figure 4 is a back plan of the collapsed chair,
Figure 5 is a side view thereof.

Figure 6 is a sectional detail showing the fastening of the pliable seat of the chair.

45 The chair comprises a pliable seat 2, of heavy fabric or other suitable material, and its front portion is attached to a front cross bar 3, having a half-round top, which is secured on the end faces 4 of inner, side legs 5—5, while the rear portion is connected to a cross bar 6' which is morticed into the lower corner of the upper, rear ends of outer side legs 6—6.

The side legs are crossed and joined in side pairs by individual coaxial pivots 7—7, and are thus axleless, this being a lower cost device than

where a long axle pivot is used. The seat 2 forms a substantial sole means connecting the upper ends of the legs and limiting opening action thereof in use.

The lower front ends of the legs are tied by a cross-piece 8 and the lower rear ends by a cross-rod 9.

A back structure comprises a pair of posts 10—10 whose lower ends are attached by suitable hinges 11—11 to the upper, rear corners of the 10 legs in such a manner that the opened back post lower end faces 12 will abut firmly against the opposed end faces 13 of the legs 6—6.

Side arms 14—14 are pivoted at 15 on the outer faces of the posts 10—10 and are hinged at 16 on the upper ends of brackets 17—17 whose lower ends are lapped on the sides of the rear ends of legs 6—6 and secured by pivots 18. Thus when the back is opened up the arms come to usable position automatically.

An important device of the invention resides in a pair of stop and brace links 19—19 whose upper ends are pivoted at 20 against the inner faces of the brackets 17 and whose lower portions have long slots 21 receiving the pivots 7—7 of respective pairs of legs. It will be seen that as the arms open with the back the links 19 will be pulled up until the lost slot motion is taken up and then the links become, with the brackets, 17 and with the abutted faces 12—13, means to brace the open back against rearward pressure of the occupant's back.

It is understood that all parts may be made of any desired size and material, and of any preferred finish, and that either screws or rivets may be employed at will in the manufacture of the chair, in securing the several elements together.

The seat is shown as both tacked at 22 on one face, and stapled at 23 to the bottom of the cross bar in Fig. 6.

Where desired washers 24 are introduced under or between the working parts and their pivots.

To unfold the collapsed chair from its position of Fig. 5, the back 10 is swung forward and upward to the position of Fig. 3, and then the inner pair of legs to the top portion of which the seat is attached is pulled forward to the limit, Fig. 3. To close the chair the procedure is just reverse, that is, the seat is collapsed by the folding up of the legs and then the back is swung down over the folded legs. It will be seen that the several legs all fold into one plane and that the back posts lie flat against the relative outer legs. The side arms and their brackets, when folded lie

within the confines of the folded back and legs; the whole making a very compact collapsed chair.

It is found by actual construction of the parts of wood of suitable hardness and plane design and smallest practicable dimensions that an extremely substantial and durable chair is produced, and that, at a very low cost.

What is claimed is:

1. A folding chair having braced, outer and inner legs crossing each other and pivoted together and all connected at the top ends by a seat, a back having side posts pivotally connected to the upper ends of the outer legs, a pair of arms pivotally connected to the side posts, a pair of brackets pivotally connected to the arms and to the outer legs, and a pair of brace links pivotally connected to the brackets of the arms and having slotted ends pivotally and slidably connected to the leg system.
2. A folding chair having braced, outer and inner legs crossing each other and pivoted together and all connected at the top ends by a seat, a back having side posts pivotally connected to the upper ends of the outer legs, a pair of arms pivotally connected to the side posts, a pair of brackets pivotally connected to the arms and to the outer legs, and a pair of brace links pivotally connected to the brackets of the arms and slidably connected to the leg system.
3. A folding chair having braced, outer and inner legs crossing each other and pivoted together and all connected at the top ends by a seat, a back having side posts pivotally connected to the upper ends of the outer legs, a pair of arms pivotally connected to the side posts, a pair of brackets pivotally connected to the arms and to the outer legs, and a pair of brace links pivotally connected to the brackets of the arms, means providing a lost motion connection between said arms and the leg system and a pliable seat con-

necting the upper ends of the inner and the outer pairs of legs and limiting the opening movement thereof.

4. A folding chair having braced, outer and inner side legs pivoted in side pairs, a back structure pivoted on the upper rear ends of said legs whose tops are connected by a seat, side arms pivotally connected to said back, and means including a lost motion link and bracket system connected to said arms and to said legs to limit opening movement of and to brace the unfolded back; the links being connected to respective arm and leg parts and the brackets being connected to respective arms and pivots of the side legs.

5. A folding chair having braced, outer and inner side legs pivoted in side pairs, a back structure pivoted on the upper rear ends of said legs whose tops are connected by a seat, side arms pivotally connected to said back, and means connected to said arms and to said legs to limit opening movement of and to brace the unfolded back, said means including foldable bracket and link devices connecting respective arms to respective side leg pairs; the brackets connecting the arms to the legs and the links connecting the brackets to leg pivots.

6. A folding chair having an axleless set of side crossed braced pairs of crossed legs, each pair having its own pivot connection, a back structure pivoted on the upper, rear ends of the legs, side arms pivoted on the said back, brackets pivoted on said arms and on said upper rear ends of the legs, a seat part connecting the tops of the legs from front to back and means connecting said arms to the pairs of legs and including side links pivoted on said brackets and having slotted ends working on the pivots which connect the legs in pairs.
